US0D1105418S

(12) **United States Design Patent** (10) **Patent No.:** **US D1,105,418 S**
(45) **Date of Patent:** **** Dec. 9, 2025**

(54) **MEDICINE INJECTOR**

(71) Applicant: **Sensile Medical AG**, Olten (CH)

(72) Inventor: **Simon Bürdel**, Rombach (CH)

(73) Assignee: **Sensile Medical AG**, Olten (CH)

(**) Term: **15 Years**

(21) Appl. No.: **29/960,283**

(22) Filed: **Aug. 29, 2024**

(57) **CLAIM**

The ornamental design for a medicine injector, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of a medicine injector showing my new design;

FIG. 2 is a perspective view thereof;

FIG. 3 is a left side view, the right side view being a mirror image thereof;

FIG. 4 is a top view thereof;

FIG. 5 is a front view thereof; and,

FIG. 6 is a back view thereof.

1 Claim, 5 Drawing Sheets
